UNITED STATES PATENT OFFICE.

JOHN W. CARD, OF CLEAR LAKE, WASHINGTON.

BUTT-CHAIN BLOCK.

1,085,017.

Specification of Letters Patent.

Patented Jan. 20, 1914.

Application filed January 9, 1913. Serial No. 741,091.

To all whom it may concern:

Be it known that I, JOHN W. CARD, a citizen of the United States, residing at Clear Lake, in the county of Skagit and State of Washington, have invented certain new and useful Improvements in Butt-Chain Blocks, of which the following is a specification.

This invention relates to improvements in butt chain blocks, and has for its object to provide a block, for the use of loggers and for similar purposes which will permit the choker line to pass through the block without becoming detached from the line.

A further object is to provide a link in one side of the block shell which will swing upon its central pivotal support and allow the rope supporting the lug to pass through unobstructed.

Another object is to provide in such a device a link which is pivoted on the central shaft and which swings freely thereon, without leaving engagement with the end portions of the shell.

I accomplish these objects by the mechanism illustrated in the accompanying drawing, in which—

Figure 1 is a horizontal sectional view showing the upper portions of the shell removed. Fig. 2 is a longitudinal vertical sectional view of same.

Referring to the drawing in detail, 18 represents the shell of the block to what may be termed the rear end of which, is secured the yoke 14, by means of the bolts 35 20. To the front end upon bolts 3, is secured the yoke 10.

In use, the block will be anchored by the cable 15, so that it will lie in the position shown in Fig. 2. If it is desirable to suspend 40 the block above the ground this may be done by means of cable 9 anchored in the yoke 10.

Transversely in the upper member 18, of the shell, is mounted the shaft 13, having the flanged cap 19, and upon its intermediate 45 portion is mounted in the usual manner the roll 4, against the lower end of which, upon the shaft 13 is loosely mounted the disk 6^a, having the radial arms 6 about its periphery, and secured in place upon the enlarged 50 journal 13^a by means of the flanged cap 13^b.

To the lower end of yoke 10 upon bolt 3 is secured the lower member 1 of the shell, which is off-set from its point of union, and extended at 1^a to engage upon the lower terminal of the shaft 13, which is extended a sufficient distance for that purpose.

The member 1 has a transverse channel 21 formed at a point from the central axis, beyond the circumference of the roll 4 and upon the arc of a circle about said axis. The inner face 2 of the channel is inclined inwardly.

The yoke 14 is extended at its lower end and off-set to correspond with the off-set portion of the member 1; and in its inner face at a distance from the axis equal to that of channel 21, is formed a channel 22 of similar shape and dimensions and having a similarly inclined inner face 2^a. The lower member may be divided and the end portion 70 united in the usual way to the yoke.

About the disk 6^a is formed a plurality of radial arms 6, each having secured therein at a point corresponding to said channels a pin 5, each carrying a roll 7 held in place by the flange 5^a, and each having an inclined bearing face 7^a conforming to and bearing upon the inclined faces 2 and 2^a of said channels. These arms will be so disposed that two or more of them will at all times lie 80 within the limits of the shell, so that two or more rolls 7 will always bear against the face 2^a of the channel 22 to sustain the yoke 14.

In operation the main line 8 will be retracted by the engine, drawing with it the haul back line 17 and the choker line 16, which are secured thereto by means of hooks 11 and 12 respectively. The haul back travels over the roll 4, and the choker line, 90 which carries the log, drops to the ground. As the log approaches the block, which is always at a curve in the line, the depending choker will engage between two of the radial arms causing the disk 6^a to rotate on the 95 axis until it comes into line with the other portion of the main line, when it will leave the arms, thus allowing the log to pass the block without obstruction and without the need of detaching and reattaching the choker 100 line, which is the present practice in logging. In this manner there is formed ample support between the shaft 13 and the yoke 14 to sustain the strain of the anchor 15; and the inclined faces 2 and 2^a will sustain the 105 corresponding rolls 7 against lateral displacement.

Having described my invention, what I claim is—

1. A pulley block having a divided side 110 member, each portion having a transverse, arcuated channel formed about a common

center, a shaft journaled in the side members, a disk mounted upon said shaft and extending beyond said channels, and retaining elements fixed in spaced relation about said disk and engaging in said channels, so as to form a connection between the divided members and permit rotation of the disk.

2. A pulley block having a divided side member, each portion having a transverse, 10 arcuated channel formed about a common center, a shaft journaled in the side members, a disk mounted upon said shaft and extending beyond said channels, pins fixed transversely in spaced relation about said disk 15 and adapted to extend into said channels, and a roller upon each of said pins adapted to engage the inner face of the channels to connect the divided members and permit rotation of the disk.

20 3. In a butt chain block, a shell having a divided side member, a shaft mounted therein, a channel formed in the free portion of said side member about said shaft as a center, a disk journaled upon the shaft, arms

25 radially disposed about said disk and extending opposite said channel, a stud secured in each of said arms and adapted to extend into said channel, and a roll upon each stud adapted to engage the inner face of the channel.

30 4. In a butt chain block, a shell having a divided side member, a shaft mounted therein, 35 a channel formed in the free portion of said side member about said shaft as a center, a disk journaled upon the shaft, arms radially disposed about said disk and extending opposite said channel, a stud secured in each of said arms and adapted to extend into said channel, a roll upon each stud adapted 40 to engage the inner face of the channel, and means to retain the roll in engagement in the channel.

45 In testimony whereof I affix my signature in presence of two witnesses.

JOHN W. CARD.
